UNITED STATES PATENT OFFICE.

WILLIAM L. JACOBY, OF LARCHMONT, NEW YORK, AND RICHARD M. HOPKINS, OF RUTHERFORD, NEW JERSEY, ASSIGNEES TO AMERICAN DISTRICT TELEGRAPH COMPANY, OF NEW YORK, N. Y., A CORPORATION OF NEW JERSEY.

AUTOMATIC SIGNALING SYSTEM FOR INDUSTRIAL ESTABLISHMENTS.

Application filed May 7, 1918. Serial No. 232,998.

To all whom it may concern:

Be it known that we, WILLIAM L. JACOBY and RICHARD M. HOPKINS, citizens of the United States, and residents, respectively, 5 of Larchmont, county of Westchester, and State of New York, and of Rutherford, county of Bergen, and State of New Jersey, have invented certain new and useful Improvements in Automatic Signaling Systems 10 for Industrial Establishments, reference being had to the accompanying drawings, which form a part hereof.

This invention relates to automatic electric signaling systems especially designed 15 and adapted for use in large industrial establishments. The general purpose of the invention is to enable certain employees or officials, whose duty it is to pass through the various departments of the establishment on 20 tours of inspection or other business, to send in to a central office, from calling stations located at various points throughout the establishment, signals that will inform the central office of the identity of the party 25 who transmits the signal and of his location. In this way the central office may be kept informed at all times of the whereabouts of such employees and may be able to communicate with them on short notice as circumstances 30 may require.

The invention consists of the arrangement of circuits and devices hereinafter described and more particularly pointed out in the claims.

35 In the accompanying drawings forming part of this specification and in which like reference numerals designate corresponding parts,

Fig. 1 is a diagrammatic view showing 40 the entire system in its preferred arrangement. Figs. 2, 3 and 4 are fragmental views in section showing details.

Referring now to the particular arrangement as shown in the drawings, 1 is a normally closed signaling circuit extending 45 from ground through battery 2 and relay magnet 3 at the central office, C. O., thence in series through the transmitter devices of the calling stations 5, 4 and 3 in turn, located 50 at various points throughout the establishment, and thence to ground. At station 5 the circuit passes through normally closed contacts 7 and 8 operated by a signal wheel 9 of transmitter 10, thence through normally

closed contacts 11 and 12 operated by signal 55 wheel 13. At station 4 it extends through normally closed contacts 14 and 15 operated by signal wheel 16 of transmitter 17, thence through contacts 18 and 19 operated by signal wheel 20. At station 3 the circuit extends 60 through contacts 21 and 22 operated by signal wheel 23 of transmitter 24 and thence through contacts 25 and 26 operated by signal wheel 27 of transmitter 28 and thence to ground. Magnet 3, through its 65 armature 4, controls a local circuit 5 which operates a suitable signal receiver 6 at the central office. This receiver may be conveniently arranged to record a dot or other character on a paper tape for each temporary 70 closing of the circuit 5.

The transmitting devices at each of the calling stations are normally sealed against operation by suitable means. In the preferred arrangement as shown in the drawings, 75 these transmitting devices at each station are sealed against operation by being enclosed in a normally locked box such as the box 29 at station 3. The transmitting devices and boxes at the several stations are 80 all similar so that the description of these features located at station 3 will be sufficient. The box 29 is provided with a hinged door or other closure 30 provided with a lock 31 designed to be operated by a key carried by 85 each employee of the establishment whose duty it is to make use of the system. The door 30 is normally held closed by a spring 32. The transmitter 24 is provided on its face with a rotatable disk 33 carrying a series 90 of apertures which may be successively marked 1, 2, 3, 4, etc. To each of the signaling parties in the establishment there is appropriated a particular characteristic number. Each party is expected to transmit his 95 own characteristic signal number when he operates a transmitter, such as the transmitter 24. If, for example, the signaling party has the number 24, then in transmitting his number he inserts his finger 100 in the aperture 2 and rotates the disk 33 until his finger comes against the stop 34, whereupon he releases the disk which, by means of its mechanism, returns to its initial position causing two rotations of the signal 105 wheel 23 and thereby makes two breaks in the signal circuit 1 at contacts 21 and 22. This closes the local circuit at the central

office twice and produces the corresponding notation in the receiving instrument. The signaling party then repeats the operation, but this time using the finger hole 4, and thereby makes four breaks in the signal circuit and produces a corresponding notation at the central office. The party in charge of the central office, having thus received the signal 24, therefore knows that the employee to whom the number 24 is appropriated has transmitted the signal. If another employee to whom a different numeral, such as 53, was operating the transmitter, he would first use the finger hole 5 and then the finger hole 3 thereby causing the numeral 53 to be received at the central office. The transmitter 24 is thus adapted to transmit a multitude of different signals characteristic of or indicating the particular party sending in the signal. Transmitter 24 is a well known mechanism in the art and its specific construction need not therefore be more fully shown or described.

After the signaling party has operated the transmitter 24 he closes and locks the door 30. In closing this door he operates another transmitting device, associated with circuit 1, which indicates at the central office a signal characteristic of the particular station from which the party has just signalled his own characteristic number. In this way the central office is informed not only of the particular individual who transmitted the signal but also the precise point in the establishment from which the signal originated. The transmitting device for sending in the station characteristic signal may be variously arranged. That shown in the drawing is an adaptation of an ordinary district messenger calling box and is fixed inside the box 29. It is provided with a signal wheel 27 and with the usual operating spring lever 35. This lever is operated by a slide bar 36 working in keepers 37 and 38 fixed on the side of the box. It carries a lug 39 fixed in place by a hinge 40 which permits the lug to turn from normal position toward the keeper 38. A coiled spring 41 connects keeper 37 and lug 39. When the door 30 is closed the parts are in the position shown in Figs. 3 and 4 in which the bar 36 is held in its inner position by the door 30. When the door is opened the bar 36 is moved by spring 41 to its outer position as shown in Fig. 1. In doing so the hinge on lug 39 permits the lug to pass from the rear side to the front side of the lever 35. When the door is closed it pushes bar 36 inward, lug 39 at the same time pushing lever 35 to the rear and winding up its associated mechanism. Just before the lug 39 reaches its innermost position, the end of the lever 35 passes beneath the lug and is thus released and is moved by its spring to the left. Its associated wheel 27

at the same time makes one complete rotation and its three teeth cause three quick breaks in the signaling circuit 1 at contacts 25 and 26. A corresponding signal is, therefore, received or recorded at the central office. It will be noted that signal wheel 20 at station 4 has four teeth and signal wheel 13 at station 5 has five teeth so that these signal wheels when operated send in signals characteristic of the stations where they are located.

It is important to prevent confusion of signals that would arise if two or more signals were simultaneously transmitted from different stations. For this purpose a locking circuit is provided which extends from the central office to the several stations and by means of which when the door of one box has been opened, all the other boxes will be locked. In the arrangement shown, this locking circuit extends from ground at the central office through battery 2 and thence through wire 42 to the several station boxes in series and to ground. It includes contacts 43 and 44 and locking magnet 45 located in the box at station 5, also contacts 46 and 47 and locking magnet 48 located in the box at station 4, also contacts 49 and 50 and locking magnet 51 located in box 29 at station 3. The contacts, locking magnets and associated devices located in the boxes are all similar so that it will be sufficient to describe such devices as located in box 29. The locking circuit is normally closed and its locking magnets are therefore normally energized. Contacts 49 and 50 tend to separate and break the locking circuit but are normally held closed by means of a lug 52 extending inward from the door 30 and pressing the contacts together. The armature 53 of magnet 51 moves up and down on pins projecting from the poles of the magnet. Projecting downward from the armature is a bolt 54 and in line with this bolt are two spaced lugs 55 fixed to the side of the box and provided with registering holes for the reception of the bolt. 56 is another lug secured to the door and provided with a bolt hole. When the door 30 is closed, lug 56 projects between the spaced lugs 55 and the bolt holes in these lugs register. The bolt 54, however, is elevated at this time because lug 52 is holding contacts 49 and 50 closed and the locking circuit is therefore closed, assuming that the boxes at the other stations are closed. When door 30 is opened, lug 56 first passes beyond the bolt 54 and thereafter lug 52 releases contact 50 and permits it to separate from contact 49. This opens the locking circuit and deenergizes locking magnet 51 which drops its bolt 54. The locking magnets at the other stations do likewise. Hence, while the door 30 is open, if an attempt is made to open a box

at any other station, the locking bolt at that station will prevent the door from being opened so that no interfering signal can be transmitted while a signal is being sent in from station 3.

When door 30 is being closed, lug 52 first closes contacts 49 and 50 thereby energizing all the locking magnets and elevating their bolts. The bolt 54 is therefore elevated to clear the way for lug 56 to move into its normal position as shown in Fig. 4.

In many cases it may be desired to communicate from the central office with the party who has just signalled from a calling station. For this purpose an ordinary telegraph key 57 at the central office is connected in the circuit 42. By operating this key a locking magnet, as 51, may be made to act as a telegraphic sounder to receive any desired message for the party at calling station 3 as soon as he has operated the transmitters at that station. It is true that the locking magnets at the other calling stations will be simultaneously operated by key 57, but the operation of these other locking magnets will in no way interfere with the reception of the desired message at station 3.

In all cases it may not be desired to keep the boxes at the calling stations normally locked or sealed and in such cases the locks 31 need not be availed of.

It is to be observed that various changes may be made in the design and arrangement of parts and the invention may be applied to various uses without departing from the scope of the invention as defined in the claims.

What we claim is:—

1. In an automatic signaling system, the combination of a signaling circuit extending from a central office to a plurality of calling stations; automatic signal transmitting means at each station associated with said circuit; signal receiving means at the central office associated with said circuit; a box having a closure for the signal transmitting means at each calling station; and a locking circuit connecting the calling stations, said locking circuit including a locking magnet located within the box at each station, co-operable with the closure of the box to engage and disengage the same, and a pair of contacts also located within the box at each station co-operating with the closure of the box to open or close the locking circuit.

2. In an automatic signaling system, the

combination of a signaling circuit extending from a central office to a plurality of calling stations; automatic signal transmitting means at each station associated with said circuit; a box having a normally locked closure for each of said signal transmitting means; means at the central office for receiving signals over said circuit; and a normally closed locking circuit including a locking magnet located within the box at each station, the armature of the magnet being normally disengaged from the closure, and a pair of normally closed contacts which are opened by opening a closure of any box, thereby permitting the armature to engage the closures of other boxes.

3. In an automatic electric signaling system, the combination of a signaling circuit extending from a central office to a plurality of calling stations; an automatic multiple signal transmitter at each calling station associated with said circuit, each of said transmitters adapted to transmit a signal characteristic of the signaling party; signal receiving means at the central office associated with said circuit; a locking circuit connecting said calling stations arranged, when the transmitters at one station are being operated, to automatically prevent the operation of the transmitters at all the other calling stations, said locking circuit including a magnet at each calling station; and a telegraph key located at the central office and connected in the locking circuit whereby the locking magnets may be operated.

4. In an automatic signaling system, the combination of a signaling circuit extending from a central office to a plurality of calling stations; automatic signal transmitting means at each station associated with said circuit; signal receiving means at the central office associated with said circuit; a box having a closure for the signal transmitting means at each calling station; a locking circuit connecting the calling stations and having means including a locking magnet at each calling station operable by the closure of any of the boxes to lock the closures of all of the other boxes; and a telegraph relay located in the central office and connected in the locking circuit, whereby the locking magnets may be operated.

This specification signed this 4th day of May, A. D. 1918.

WILLIAM L. JACOBY.
RICHARD M. HOPKINS.
